CLAIM

The ornamental design for the gateway device, as shown and described.

DESCRIPTION

FIG. 1 is a perspective view of a gateway device in accordance with the present invention.

FIG. 2 is a top view of the gateway device of FIG. 1; FIG. 3 is a bottom view of the gateway device of FIG. 1; FIG. 4 is a front view of the gateway device of FIG. 1; FIG. 5 is a back view of the gateway device of FIG. 1; FIG. 6 is a left side view of the gateway device of FIG. 1; and,

FIG. 7 is a right side view of the gateway device of FIG. 1. The broken lines are directed to environment and are for illustrative purposes only; the broken lines form no part of the claimed design. In addition, the unshaded surfaces in the FIG. 3 view that directly adjoin the claimed solid line edges form no part of the claimed design.
